UNITED STATES PATENT OFFICE.

CHARLES O. VEST, OF BLUEFIELD, WEST VIRGINIA.

JOURNAL JACK-BLOCK AND WHEEL-CLAMP.

1,382,332.

Specification of Letters Patent. Patented June 21, 1921.

Application filed December 1, 1920. Serial No. 427,507.

To all whom it may concern:

Be it known that I, CHARLES O. VEST, a citizen of the United States, residing at Bluefield, in the county of Mercer and State 5 of West Virginia, have invented a certain new and useful Improvement in Journal Jack-Blocks and Wheel-Clamps, of which the following is a full, clear, and exact description.

10 The primary object of this invention is to provide an implement for use in removing, or adjusting, or repairing the journal boxes of railway car trucks, and to clamp the wheel to a rail of the track while the work 15 is progressing.

The invention consists of a base-piece on which a lifting jack may be supported, having an upwardly inclined end provided with ways in which is arranged an adjustable 20 wheel clamping member, herein referred to as the wheel clamp, adapted to engage the back of the rim of the wheel and hold the wheel on the rail while the jack is being operated to lift the journal box free 25 of the axle, said clamp having ratchet teeth engaged by a spring dog or bolt to hold it in given adjustment, as I will proceed now to explain and finally claim.

In the accompanying drawings illustrating 30 the invention, in the several figures of which like parts are similarly designated, Figure 1 is a side elevation showing the implement in use. Fig. 2 is an end elevation, with the truck frame, track rail and 35 part of the wheel in cross-section. Fig. 3 is a sectional elevation, on a larger scale, taken on line 3—3 of Fig. 2. Fig. 4 is a cross-section taken on line 4—4 of Fig. 3. Fig. 5 is a perspective view of the implement alone.

1 is a car wheel, having the ordinary or any approved rim 2, and 3 is the axle. 4 is a journal box, also of ordinary or approved construction, mounted in the side frame 5 of 45 the truck, and adapted to receive the journal of the axle. 6 is the track rail. 7 is an ordinary or approved lifting jack.

The implement of this invention comprises a base-piece 8, of metal, which may be 50 supplied at one end with a suitable hand-hold 9 for handling it, and at its other end is an outwardly inclined upright 10, slotted longitudinally, as at 11, and provided with the opposite grooves 12. The wheel-clamp 55 13 has the shank 14 arranged in the slot 11 and said shank is provided with lateral

flanges 15 and 16 which travel in the grooves 12. The flange 15 is made as a ratchet and the teeth thereof are engaged by a spring dog or bolt arranged in the 60 upright 10 at right angles thereto. This dog has the beveled nose-piece 17 to engage the ratchet teeth; the squared or angular shank 18 engaging a complementary hole in the member 10, or otherwise constructed to 65 prevent the dog from turning; the spring 19 engaging the dog and normally forcing its nose into engagement with the ratchet teeth, and the operating knob or handle 20, by which the dog may be disengaged from 70 the ratchet teeth. The upper end of the shank 14 has the outwardly projecting lip 21 shaped to conform, at least approximately, to the back of the rim 2 of the 75 wheel.

22 is a hole in the upright 10 opposite the spring dog or bolt, for use in inserting and removing the dog or bolt. It will be noticed that the operating knob or handle 20 is shown as detachable from the shank 18, so 80 that the dog or bolt may be removed at pleasure.

In operation, the base-piece 8 is placed at right angles to the wheel, on the road-bed or other suitable support, and the wheel clamp 85 is then pressed down so that its lip 21 will engage with the back of the rim of the wheel, as shown in Fig. 2. This will serve to hold the wheel on the track while the lifting jack 7 is operating upon the journal box 4. The 90 lifting jack is supported upon the base-piece 8 which constitutes the jack-block of this title. Obviously any tendency of the lifting-jack to raise the car wheel from the track is resisted by the wheel clamp, and consequently the dislocation of the journal box is 95 effected surely and expeditiously.

The outward inclination of the upright 10 is an important feature of the machine, in that it affords room to remove and replace 100 bearings on the car-wheel journals under any and all conditions. For example, if the wheel on a journal to be operated upon should stand over a rail-joint provided with angle-bars as usual, it would be impossible to position a machine having a perpendicular upright so as to have its clamp reach over the obstruction into engagement with the wheel; whereas the inclination of the upright compensates for the obstruction and 105 permits the engagement of the wheel by the clamp. And not only is this outward in-

clination of the upright effective to meet this condition, but it is equally effective where other track obstructions may occur and where there are no such obstructions.

5 Variations in details of construction and arrangement of parts are considered to be permissible within the principle of the invention as herein claimed.

What I claim is:—

10 1. A journal jack-block and wheel clamp, having a base-piece to support a lifting-jack, said base-piece provided at one end with an outwardly inclined upright having a longitudinal slot and grooves adjacent to said slot, a correspondingly inclined wheel clamp having a shank provided with longitudinal side flanges, the said shank slidable in the slot and its flanges entering said grooves, a wheel-engaging lip projecting outwardly 15 from the shank, and coöperating means on the upright and wheel clamp to hold the wheel clamp in adjusted position.

20 2. A journal jack-block and wheel clamp, having a base-piece to support a lifting-jack and provided at one end with an outwardly inclined upright slotted longitudinally and provided with opposite grooves opening into said slot, and a wheel clamp having a lat-

erally flanged shank engaging said slot and grooves, one of the flanges on said shank 30 having teeth, and a spring dog or bolt mounted in the said upright and engaging said teeth, and a clamping lip on said shank to engage the back of the rim of a car wheel.

3. A journal jack-block and wheel clamp, 35 having a base-piece to support a lifting-jack and provided at one end with an outwardly inclined upright slotted longitudinally and provided with opposite grooves opening into said slot, and a wheel clamp having a shank arranged in said slot and provided with lateral flanges engaging the grooves, one of said flanges having ratchet teeth, and a spring dog or bolt arranged in said upright at right angles to 40 the toothed flange and engaging the latter, and a lip at the outer end of the shank to engage the back of a car wheel rim.

In testimony whereof I have hereunto set my hand this 13th day of November A. D. 50 1920.

CHARLES O. VEST.
